ACTION TOY

Herman G. Fisher, East Aurora, N. Y., assignor to
Fisher-Price Toys, Inc., East Aurora, N. Y.

Application June 19, 1940, Serial No. 341,335

10 Claims. (Cl. 46—99)

This invention relates to action toys and has for one of its objects to provide an improved toy of such form that the operating elements thereof are of improved form and are adapted to be made and assembled in accord with simplified manufacturing processes. Other objects and advantages of the invention will appear in the specification herein.

In the drawing:

Fig. 1 is an elevation of a toy of the invention; Fig. 2 is a bottom plan view of the toy of Fig. 1;

Fig. 3 is a perspective, on an enlarged scale, of a portion of the actuating mechanism of the toy; and

Fig. 4 is a plan of a detail of the actuating mechanism at an intermediate stage of manufacture thereof.

The toy comprises generally a body 10 which may be so shaped externally as to simulate the outlines of an animal or other toy figure, and may be conveniently formed of wood or any other suitable material. The body member 10 is intermediate grooved as at 12 and 14 at its front and bottom side edges, respectively, to accommodate the actuating elements of the toy in substantially concealed relation therein, as will be more fully explained hereinafter.

The body member 10 is supported for rolling movement across a floor or the like by means of front and rear pairs of traction wheels 16 and 18, respectively; the pairs of wheels being supported relative to the body by means of front and rear axles 20 and 22, respectively. Spacer members 17 of sleeve form are mounted upon the axles between the traction wheels and the body member 10. The front axle 20 is rotatably mounted in the body member 10 and is keyed to the wheels 16. For this purpose the shaft 20 may be conveniently formed of square section so as to provide the keyed connection between the shaft and the wheels.

A cam device 26 is mounted upon the squared axle 20 at its central portion so as to be disposed within the slotted portion of the body member and is adapted to rotate with the axle 20 to actuate the moving members of the action toy in response to rolling movement of the toy, as when pulled by a pull-cord 28. The cam device 26 is formed of sheet metal and first cut into the form as illustrated in Fig. 4 so as to provide a sheet metal body having a reduced center section 30, oppositely extending end finger portions 32, and intermediate body portions 34 in which are formed square openings 36 for fitting upon the axle 20. The cam device 26 is then folded at its

center section into the final U-shaped form as illustrated in Fig. 3 whereby the openings 36 are brought into registering alignment so that the cam is adapted to be simply slid onto the axle 20 to its operative position at the center section thereon.

Thus, the cam 26 is free floating upon the axle 20 and will adjust itself to differences in relative arrangements of adjacent parts of the toy, as may be due to inaccuracies in manufacture and assembly thereof or the like; and when the cam 26 is mounted upon the axle it is maintained in proper lateral position thereon by the guiding action of the opposite wall portions of the body 10 of the slotted portion thereof.

As illustrated in Fig. 1, the cam device 26 is operatively associated with a movable lip member 40, which is pivotally mounted upon the toy body as at 42, by means of a pitman 44 pivotally connected with the lip member by means of an inturned finger 46, as at 48. The lower end of the pitman 44 is rotatably mounted eccentrically of the axle 20 by means of engagement of the axle and cam combination by the lower end 50 of the pitman which is of circular form and looped about the axle 20 and the central portion 30 of the cam device. Thus, as the axle 20 rotates the lower end of the pitman is caused to move through an orbit having its center at the axis of the shaft 20; the extending finger portions 32 of the cam device being sufficiently spaced apart to clear the shaft of the pitman 44 during such movement. Consequently, the pitman 40 is given oscillative movements about the pivotal connection 42; and it will be understood that the element 40 may be any element of a toy that is to be oscillated to simulate life like movements.

It will be appreciated that to assemble the cam 26 in conjunction with the shaft 20 and the loop 50 of the pitman 44 the loop 50 will necessarily be first mounted upon the cam in proper position thereon and the shaft 20 will then be threaded through the opposing wall portions of the cam member and within the loop 50 to the position illustrated in Fig. 3. The unit is then in self-locking assembled relation, and it is impossible for the side wall portions of the cam member to move relative to one another to any substantial degree because of their being locked upon the shaft 20. However, the unit may be purposefully disassembled with complete facility by simply sliding the shaft 20 through the cam member and out of engagement therewith.

The side wall portions of the cam member are provided with projecting portions 31 which abut

the adjacent portions of the loop 50 to prevent the latter from moving laterally with respect to the bearing portion 30 of the cam member. Thus, the projecting portions 31 function as guide means to maintain the loop 50 at all times in operative engagement with the bearing portion 30 of the cam member.

A sound producing device is mounted adjacent the lower portion of the body 10 and comprises essentially a sounding board 52 of cardboard or the like and a spring striker 54 for intermittent striking of the sounding board to produce sound vibrations. The sounding board 52 is arranged to span the slot at the lower portion of the body 10 and is conveniently mounted in rigid relation upon the opposite extending body portions thereof by means of staples 56 driven through the sounding board and into the material of the body 10. The striker 54 is of spring type and is mounted at one of its ends as by being coiled about the axle 22. An intermediate portion of the spring is bent to provide a protuberance as at 58 for bearing against the sounding board 52. An abutment bar 60 bears against an upper part of the spring 54 to normally maintain the protruding portion 58 in bearing relation against the sounding board. The free end 62 of the striker is arranged to be actuated by the fingers 32 of the cam 26 in such manner as to be periodically lifted by the cam and subsequently released for return to normal position. During the striker lifting operation the portion 58 of the striker is withdrawn from the sounding board but returns thereto upon release by the cam, whereby the striker vibrates against the sounding board and produces an animal simulating noise.

The camming fingers 32 being spaced apart are adapted to compensate for inaccuracies in connection with the manufacture or assembly of other portions of the toy. For example, in the toy of the drawing, the fingers 32 will be so spaced as to span a dimension slightly less than the width of the member actuated thereby, and consequently even though the movable member may not be accurately located in the body of the toy either one or both of the finger members 32 will come into contact with the movable member upon actuation of the toy, and the effective operation will be fully as complete as though the toy parts were accurately manufactured and aligned in accord with the plan thereof.

Also, the extending finger portions 32 of the cam may be disposed radially at any desired angular relationship with respect to the direction of the offset extension of the eccentric portion of the device. Consequently, although the drawing illustrates the finger portions 32 as extending in substantially diametrically opposed relation with respect to the eccentric portion of the device, the finger portions 32 may with equal facility be inclined upwardly or downwardly at any other desired angular relationship with respect to the shaft 20. Thus, any desired time relation between effects of operation of the eccentric and cam portions of the device may be obtained. The eccentric portion of the device is a complete and novel structure in itself and may be used with great facility in connection with various forms of action toys, either independently of or in combination with the camming portion previously described and illustrated in the drawing.

Thus, it is understood that through use of an improved and simplified organization of actu-

ating parts a toy of improved form is provided. The operative parts of the device are susceptible of manufacture by means of most simple manufacturing processes, and the assembly of the parts is of such simplified nature that the toy of the invention may be economically manufactured in accord with large scale production and methods.

Although only one form of the invention has been shown and described in detail, it will be apparent to those skilled in the art that the invention is not so limited but that various changes may be made therein without departing from the spirit of the invention or the scope of the appended claims.

I claim:

1. An action toy including a body member bifurcated at a lower edge portion thereof intermediately of its outer side wall portions to form spaced depending outer wall portions, rotating shaft means extending through the bifurcated portion of said body member, cam means mounted upon said shaft means within the interior of said bifurcated body portion, a sounding board mounted across said depending wall portions of said body member and spanning said bifurcated body portion, sound producing means operatively associated with said sounding board and said cam means for actuation by the latter to produce sound effects in cooperation with said sounding board, said sound producing means being disposed within the interior of said bifurcated body portion and substantially concealed from outer view.

2. An action toy including a body member bifurcated at a lower edge portion thereof intermediately of its outer side wall portion to form spaced depending wall portions, rotating shaft means extending through the bifurcated portion of said body member, cam means mounted upon said shaft means within the interior of said bifurcated body portion, a sounding board mounted across said depending wall portions of said body member and spanning said bifurcated body portion, sound producing means operatively associated with said sounding board and said cam means for actuation by the latter to produce sound effects in cooperation with said sounding board, said sound producing means being disposed within the interior of said bifurcated body portion and substantially concealed from outer view, said sound producing means being in the form of a leaf spring rigidly mounted at one of its ends upon said body and having its other end disposed within the path of movement of said cam device and adapted to impinge at an intermediate portion thereof against said sounding board.

3. An action toy including an upright body member mounted upon front and rear traction wheels for rolling movement across a supporting surface, said body member being bifurcated to provide a recess therein at its bottom edge, said traction wheels being mounted upon front and rear axles respectively extending through said recess, cam means mounted upon one of said axles and disposed substantially within said recess, a sounding board mounted upon said body member and spanning said recess at a position between said front and rear traction wheels, a resilient striker disposed within said recess and looped about said rear axle at one of its ends and bearing against an abutment portion of said body member at a position spaced from said rear axle so as to be mounted in cantilever fashion,

the free end of said striker being disposed within the orbit of said cam device, said striker being arranged to intermittently contact with said sounding board at a position intermediate of said cantilever mounting and said free end for production of sound effects in response to actuation of said striker upon rotation of said front traction wheels.

4. In an action toy, a combination eccentric bearing and cam device for mounting upon a rotating axle adapted to impart oscillative movements to a plurality of movable members in response to rotation of said axle, comprising a U-shaped body member having parallel spaced side portions transfixed by said axle and keyed thereto, said side portions being joined by a closed end portion at a position spaced from said axle thus providing in cooperation with said axle a pair of spaced parallel members, a ring member mounted upon said spaced members for rotation thereon about a center offset from the axis of said axle and for revolution about said axis of said axle upon rotation of the latter for actuation of movable elements of said toy, said side members having parallel spaced finger portions extending oppositely from said closed body portion for intermittent cam-like engagement with other movable elements disposed within the orbit of movement of said finger members upon rotation of said axle.

5. In an action toy a movement translating device keyed to a rotating axle, said device comprising an element cut from sheet metal into the form of a symmetrical elongate body having a reduced center portion at the plane of symmetry thereof and reduced extending end portions, the body portions intermediate of said reduced center and end portions being apertured, said body member having been subsequently bent at said center portion into U shaped form with said intermediate body and finger portions disposed in parallel spaced relation, said device being mounted upon said axle by threading of said axle through said apertured body portions.

6. In an action toy, a body member, an element movably mounted upon said body member, a shaft rotatably mounted upon said body member, a U shaped device having a closed end portion and parallel spaced side portions fixed to said shaft in such manner that said closed end portion is disposed parallel to and spaced from said shaft, said closed end portion and said shaft in the region between said side portions being adapted to provide spaced bearing devices for mounting of a ring-like movement transmitting member thereon, said side portions being extended to guide said ring-like member and to maintain the latter in operative position upon said bearing devices.

7. In an action toy, an eccentric bearing device for mounting upon a rotating axle adapted to impart oscillative movements to a plurality of movable members in response to rotation of said axle comprising a U-shaped body member having parallel spaced side portions transfixed by said axle

and keyed thereon, said side portions being joined by a closed end portion at a position spaced from said axle thus providing in cooperation with said axle a pair of spaced parallel members, a ring member mounted upon said spaced members for rotation thereon about a center offset from the axis of said axle and for revolution about said axis of said axle upon rotation of the latter for actuation of movable elements of said toy.

10 8. In an action toy, a movement translating device keyed to a rotating axle thereof, said device comprising an element cut from sheet metal into the form of a symmetrical elongate body having a reduced center portion at the plane of symmetry thereof, said body being apertured symmetrically of said plane of symmetry and subsequently bent at said center portion into U-shaped form with opposite body portions disposed substantially in parallel spaced relation for mounting upon a driving axle by means of threading the latter through the apertured portions of said body.

15 9. In an action toy, a movement translating device keyed to a rotating axle thereof, said device comprising an element cut from sheet metal into the form of a symmetrical elongate body having a reduced center portion at the plane of symmetry thereof, said body being apertured symmetrically of said plane of symmetry and subsequently bent at said center portion into U-shaped form with opposite body portions disposed substantially in parallel spaced relation for mounting upon a driving axle by means of threading the latter through the apertured portions of said body, said reduced center portion being thus disposed in spaced parallel relation with respect to the line of said axle and adapted to provide in cooperation therewith spaced bearing members for mounting thereon of a circular bearing member, said opposed parallel body portions being provided with portions adapted to extend into bearing relation with respect to said bearing member for preventing lateral displacement thereof from said reduced center section.

20 10. In an action toy, a body bifurcated to provide an intermediate slot to accommodate toy actuating means in concealed relation within said body, a pair of traction wheels disposed at opposite sides of said body and mounted upon a squared axle, said squared axle being rotatably mounted upon said body and having its central portion disposed within said slot, a sounding board mounted upon said body at a marginal edge portion thereof in such manner as to span said slot, a cantilever spring device disposed within said slot and mounted at one of its ends upon said body and having its free end adjacent said axle, and cam means operatively associated with said axle adapted to successively deflect said spring from normal position and then to release it for sound producing movement against said sounding board upon rotation of said traction wheels.

HERMAN G. FISHER.
